FREQUENCY MODULATION RECEIVER

Clarence W. Hansell, Port Jefferson, N. Y., assignor to Radio Corporation of America, a corporation of Delaware

Application June 17, 1941, Serial No. 398,391

6 Claims. (Cl. 250—20)

This invention relates to new and improved methods of and means for the reception of wavelength modulated carrier current. In its broader aspects it involves new and improved methods of and means for carrying out the fundamental principles of frequency modulation reception which were described in my United States Patent No. 1,813,922. In the said patent I described a means for providing constant energy, or constant electrical charge, per cycle of an intermediate frequency carrier current in a superheterodyne frequency modulation receiver, followed by means for integrating and utilizing the successive energies or currents to provide an output current, or increment of output current, proportional to the frequency of the intermediate frequency current. That is, I provided means for producing equal energy or current pulses at a rate determined by the frequency of an intermediate frequency carrier current and utilized these pulses to produce a flow of power, or of current, which varied in proportion to frequency variations of the carrier current.

In describing my invention reference will be made to the attached drawings wherein: Figures 1 to 6 inclusive each show a modification of a wave length modulated wave demodulator arranged in accordance with my invention and Figs. 7, 8, 9 show further modifications. In the arrangement of Figure 1 received radio signals are supplied from antenna A to circuits in unit 2 comprising radio frequency amplifiers, a source of oscillations, a first detector and I. F. amplifiers. The radio signals are heterodyned down in unit 2 to an intermediate frequency, amplified and applied by way of resistances 6 and 8 to the grids 10 and 12 of a pair of vacuum tubes 14 and 16 which are provided with regeneration sufficient to produce a condition of unstable equilibrium. The regeneration may be obtained in various ways. In a preferred embodiment the grid 18 of tube 14 is coupled by resistance 20 and condenser 22 to the anode 24 of tube 16, while the grid 25 of tube 16 is coupled by resistance 26 and condenser 28 to the anode 30 of tube 14. These couplings provide regeneration to produce an unstable condition so that over the operating frequency range, one tube or the other carries a relatively large anode current while the opposite tube carries zero or very low anode current. The transfer of current from one tube to the other takes place twice per cycle of the intermediate frequency input current and is accomplished in a time period which is short compared with the time of one cycle of the intermediate frequency current.

The two tubes have their anodes 24 and 30 coupled in push-pull relation by the primary winding 40 of a transformer 42, the secondary winding 44 of which is coupled to the anodes 46

and 48 of a double diode 50. The tubes 14 and 16 are coupled by the transformer 42 to the rectifier 50 which, in turn, supplies current through a low pass filter 52 to an audio amplifier 54 and loudspeaker 56.

In operation the intermediate frequency current controls the frequency rate at which the two tubes, with their circuits, throw the current balance from one tube to the other but the 10 generative feedback determines the quickness of the transition. Therefore, the wave form of current pulses, and the magnitude of electrical charge per pulse delivered to the rectifier 50 are substantially independent of the pulse frequency 15 rate. Consequently, the mean direct current passed through the rectifier 50 and low pass filter 52 to the load 54 and 56 is substantially proportional to the pulse rate, provided the load impedance is not too high in comparison with the 20 effective impedance of the source of current for the load.

With this combination, when a frequency modulated radio carrier is being received, there is a corresponding modulation of the intermediate 25 frequency and of the pulse rate so that the rectified current, after going through the low pass filter, varies in magnitude substantially in proportion to the frequency and has variations corresponding to the modulation of received currents.

In the arrangement of Fig. 1, I have shown 30 tubes having three grids placed successively in the electron stream between cathode and anode. In each tube one grid receives the intermediate 35 frequency control potential, another acts as a screen between tube input and output circuits and the third is utilized for feedback potentials to provide the desired instability of current balance between the two tubes. The two tubes and 40 their circuits are closely related to the tripping circuit invented by my associate, J. L. Finch, as, for example, disclosed in United States Patent No. 1,844,950, dated February 16, 1932, which has 45 found wide application in communications systems.

Since, as pointed out above, the magnitude of the electrical charge per pulse delivered to the rectifier 50 is substantially independent of the pulse frequency rate the arrangement of Figure 50 1 automatically performs the functions of an amplitude limiter and frequency modulation detector, as used in prior art frequency modulation receivers, but performs the functions with simpler and lower cost equipment which produces 55 less distortion when correctly proportioned.

In Figure 2, I have shown another form of frequency modulation detector in which intermediate frequency currents from unit 2 are supplied by coupling condensers 60 and 62 and resistances 64 and 8 to the control grids 10 and 12 of two

tubes 14 and 16. Biasing potential for the grids 10 and 12 is supplied through a tap on an inductance 64. The anodes 24 and 30 are tied together and coupled by condenser 66 to a rectifier 49. The applied I. F. currents cause anode currents to flow in one tube or the other at all times except while the input intermediate frequency potential is passing through zero. At these times, for very brief periods, which occur twice per cycle of input current, the anode currents of both tubes cease. The inductance 68 between the anode direct-current power supply and the anodes tends to keep an approximately constant flow of current through itself. Consequently, when both tubes cut off their anode currents a current pulse is delivered through the condenser 66 to the rectifier 49. Rectified current derived from the pulses is filtered by 52 and associated circuit elements to remove currents of the pulse frequency leaving direct current and modulation current components. The direct current may be by-passed by transformer windings, and the remaining modulation frequency current amplified in 54 and applied to the loudspeaker 56.

In this arrangement the current pulses tend to vary in length as the input intermediate frequency varies and this tends to decrease the useful modulation output. To overcome this effect the inductance 68 between the power source and the tube anodes may be adjusted to a lower value so that, at lower pulse frequencies, the current in the inductance will change during a pulse period.

In Fig. 3 I have shown a third form of frequency modulation receiving system in which frequency modulated intermediate frequency currents are applied differentially to the grids 70 and 72 of a multi-grid vacuum tube 74. In the arrangement shown I have indicated a pentode type of vacuum tube 74 having three grids 70, 72 and 76 in series along the electron stream between the cathode 78 and anode 80. The first and second grids 70 and 72 are maintained at zero or at somewhat positive average potentials and the third grid is maintained at a somewhat more positive average potential. Direct current potentials for so biasing the grids are supplied by appropriate tabs on potentiometer resistance 75.

Due to the intermediate frequency input potentials applied to grids 70 and 72 one grid or the other will always be at a negative potential, and will block off the anode current, except for a brief interval of time when the intermediate frequency input potentials are passing through zero. At these brief time intervals, repeated twice per cycle of input potential, the tube 74 is made conducting between anode and cathode and discharges the condenser 86 connected between anode cathode.

The rate or frequency at which the condenser is discharged is determined by the frequency of the intermediate frequency current and varies in accordance with the modulation of the frequency. Consequently, the average or direct-current potential across the condenser 86 tends to vary in inverse proportion to the frequency while the average current through the tube tends to vary in proportion to the frequency. Then, so long as the condenser discharge through the tube has a time constant which is shorter than the time duration of the tube conducting periods, and the circuits supplying charge to the condenser have time constants which are long compared with the longest time period between conducting pulses, I obtain a power input current tending to

vary in proportion to the input frequency. This current variation, and a corresponding potential variation may be utilized to supply modulation frequency output power, which, in the arrangements illustrated, is amplified in 54 and applied to a loudspeaker 56. Audio transformer 85 couples amplifier 54 to the plate circuit of tube 74.

In Fig. 4 I have shown a frequency modulation receiver in which I employ what is commonly known as a multivibrator circuit. This circuit is capable of self-oscillation with a very distorted wave form of vacuum tube currents. As shown, the multivibrator comprises tubes 90 and 92 with the grid 94 coupled by condenser C to the anode 95 of tube 92. The grid 96 of tube 92 is coupled by condenser C₂ to the anode 97 of tube 90. The tubes so cross connected operate to generate waves of a frequency controlled in part at least by the values of condensers C and C₂ and of the resistances R₁, R₂, R₃ and R₄ of the circuits. The multivibrator consists essentially of a two-stage resistance coupled amplifier, with output from the anode 95 of the second stage fed back to the control electrode 94 of the first stage. When the circuits are oscillating the second tube 92 draws large pulses of current followed by longer periods of no current during which the condenser 98 connected from anode 95 to the cathode 99 of the second tube is being charged. The time between pulses, and therefore the average current through the second tube is controlled by the intermediate frequency input power supplied across R₄, which controls the frequency of tripping of the circuit. This average current varies in accordance with the frequency modulation. The modulation frequency currents are supplied from the resistance R₄ to the transformer 103 and thence through a low pass filter included with amplifier 54'. In this manner the modulation frequency currents are derived, amplified and utilized.

In Figure 5 I have shown a frequency modulation receiver in which a blocking oscillator, as it is called in the art, has its frequency of action determined by input intermediate frequency currents. This blocking oscillator comprises a tube 100 having its grid 102 regeneratively coupled to its anode 104 by the windings of a transformer 106. A grid leak 108 and condenser 110 is included in the grid connection and this resistance and condenser combination taken with the circuit elements determines in part the frequency of operation of the oscillator. The circuit is such that when an oscillation is started it builds up until a blocking voltage is developed therein on the grid 102. The building up and blocking action is rapid and current flows in short high peaks. The intermediate frequency input current to the blocking oscillator supplied across resistance 112 determines the time of starting of the pulses but, once the pulses are started, the blocking oscillator feedback through transformer 106 takes over control of the tube and forces the tube to operate and pass a short high peak of current. The tube 100 then blocks due to high negative potential, developed by the action of the grid leak and condenser, and is ready for the next cycle of wave length modulated intermediate frequency input from stage 2. The building up and blocking action is made faster than the time of a half cycle of the highest intermediate frequency, but the time period within which the anode current of tube 100 would remain cut off between pulses is made equal to or greater than

the time of one cycle of the lowest intermediate frequency produced by the useful modulation.

Across grid to cathode of the oscillator tube 100 there appear short high peaks of potential. These peaks are supplied by lead 114 to the grid 116 of the tube 118 of the following stage. The tube 118 is a condenser discharge tube. This tube has a condenser 120 connected between its anode 117 and cathode 119. In consequence, at each cycle of the intermediate frequency input current the grid 116 becomes less negative and the condenser discharge tube 118 becomes conductive and discharges the condenser 120 connected between its grid and cathode. The condenser then is charged again partially or wholly from the positive anode current supply. The mean or average potential appearing across the condenser 120 is dependent upon the frequency at which tube 118 is biased conductive and at which the condenser discharges. This average potential therefore varies up and down in accordance with the frequency modulation present in the intermediate frequency input. Consequently, the potential across the condenser 120, after elimination of frequency components at frequencies above the useful modulation frequencies, including the intermediate frequency and its harmonics, represents the useful modulation which it is desired to receive. Consequently, output taken from the condenser 120 passed through a low pass filter and audio amplifier 54" may be used to drive a loudspeaker or any other suitable output device.

In the arrangement of Fig. 5, as well as in the arrangements shown in the other figures, a variation in amplitude of the intermediate frequency currents and potentials has very little, if any, effect upon the operation of the detecting system, provided the input is above some minimum required level. Consequently, the systems shown act as amplitude limiters as well as frequency modulation detectors.

In Fig. 6 is shown a modification of Fig. 5 in which pulses from a blocking oscillator are passed by coupling condenser 125 into a rectifier 126 to provide a rectified current having an average value which varies substantially in proportion to the frequency of the intermediate frequency current. This arrangement also provides amplitude limiting and frequency modulation detection.

The system of Figure 1 may be modified as illustrated in Figure 7. In Figure 7 the antenna 1 and heterodyning and intermediate frequency amplifying means reduces the frequency of the received wave length modulated wave while increasing the percentage modulation thereof and feeds the same to transformer 5 and thence by way of resistances 6 and 8 to the control grids 18 and 25 of tubes 14 and 16 which in this modification are triodes. These grids 18 and 25 are cross connected by resistances 23 and 21, respectively, to the anodes 24 and 30, respectively, to form a tripping circuit similar to that of Figure 1. The tubes 14 and 16 as explained in detail in connection with Figure 1 alternately pass current. The duration of the impulses depends on the constants of the tube circuits and is substantially independent of the amplitude of the input. The frequency of reversal, twice per cycle of applied intermediate frequency current, depends on the frequency of the input. The alternating current output is fed to transformer 42 and rectified as in Figure 1.

The arrangement of Figure 8 is a modification

having features of the arrangements of Figures 2 and 5. In Figure 8 a single pulsing tube 14' replaces the pulsing tubes 14 and 16 of Figure 2. A transformer 65 replaces the coupling including condensers 60, 62, inductance 64 and resistances 6 and 8 of Figure 2. The pulses in Figure 8 are fed to a condenser discharge tube 118 in many respects similar to tube 118 of Figure 5. The tube 118 controls the rate of discharge of condenser 121 which is charged at a rate dependent principally on the value of resistance 123. The conductivity of tube 118 is controlled by the pulses, which are of substantially constant amplitude and time duration, are fed through condenser 66 is a function of the frequency of the intermediate frequency output of the amplifier in 3. The time constant of the assembly including condenser 121 and resistance 123 is made less than the time between pulses (output from 14') at the highest pulse rate which corresponds to the highest modulation frequency.

In Figure 9, which is in some respects similar to the modification of Figure 5, currents picked up by the antenna are first heterodyned to a lower frequency and amplified to a higher power level, after which they are delivered through a coupling transformer to a pulsing oscillator comprising one-half of the twin element triode vacuum tube 100'. This oscillator serves the same purpose as the oscillator associated with tube 100 of Figure 5. The oscillator is so designed and adjusted that, by itself, it would cause short high peaks of anode current at a frequency somewhat less than the lowest intermediate frequency delivered to it.

When the frequency modulated intermediate frequency current is delivered to the oscillator it increases the pulsing oscillation rate to make it equal in frequency to the frequency of the intermediate frequency current. Then the oscillator frequency is modulated as the intermediate frequency current is modulated by the useful signals.

By means of a connection from the control electrode 102 of the pulsing oscillator to control electrode 116 of a discharge circuit a condenser 101 connected with the anode circuit is discharged once each cycle of the intermediate frequency current. The condenser 101 is connected with a positive potential current source through an impedance, which may be the resistance 107 shown.

Preferably the adjustments are made such that the condenser is discharged to a rather low fixed value of potential at each pulse from the pulsing oscillator. The potential across the condenser then rises due to charging current from the source until the next pulse discharges the condenser again. As a consequence of this action the mean effective potential of the condenser is modulated by a modulation in the frequency of the pulsing oscillator under the control of the received current. This modulation in mean effective potential causes modulation frequency currents to flow through the primary winding of the output transformer, which may be filtered and utilized as explained in connection with the other figures.

In the operation of the arrangement of Figures 4, 5, 6 and 9 it is not essential that the frequency of operation of the pulsing oscillators be equal to the frequency of the intermediate frequency current. Instead, the oscillators may operate at $\frac{1}{2}$, $\frac{1}{3}$, $\frac{1}{4}$, etc. of the frequency of

the intermediate frequency current provided the percentage modulation of frequency of the intermediate frequency current is not too great.

I have illustrated my novel frequency modulation detector circuits as applied to radio receivers but it should be apparent that they are also applicable to any kind of carrier wave frequency modulation communication or telemetering system, including electrical communication over wire circuits, through wave guides, and signalling by vibrational waves through gases, solids or liquids, such as submarine signalling. They may be used advantageously in receiving sub-carrier frequency modulated signals in multiplex systems and in facsimile communications systems such, for example, as disclosed in C. W. Hansell Patent No. 1,819,508, dated August 18, 1931; C. W. Hansell Patent No. 2,103,847, dated Dec. 28, 1937; R. H. Ranger Patent No. 1,830,242, dated Nov. 3, 1931; J. N. Whitaker appln. Ser. No. 311,495, filed Dec. 29, 1939; H. O. Peterson appln. Ser. No. 384,628, filed Mar. 22, 1941; H. Tunick, appln. Ser. No. 369,800, filed Dec. 12, 1940; H. O. Peterson appln. Ser. No. 341,285, filed June 19, 1940; and H. H. Beverage Patent No. 2,025,190, dated Dec. 24, 1935.

The invention, and the detail arrangements shown, provide for substantial suppression of amplitude modulations, or amplitude limiting, as well as for demodulation of frequency modulated waves with simpler and less expensive equipment than heretofore used.

I claim:

1. In a receiver of angular velocity-modulated carrier waves, a demodulator comprising a first electronic device having at least a cathode, a wave input electrode and an output electrode, means regeneratively coupling the output and input electrodes to provide an oscillator, means operatively associated with the oscillator normally to cause high peaks of output electrode current of short duration at a frequency close to the lowest wave frequency supplied to the receiver, a second electron discharge device having electrodes coupled to said oscillator device to derive therefrom a voltage representative of the modulation of applied waves, and a modulation voltage utilization circuit coupled to the second device.

2. In a receiver of angular velocity-modulated carrier waves, a demodulator comprising a first electronic device having at least a cathode, a wave input electrode and an output electrode, means regeneratively coupling the output and input electrodes to provide an oscillator operating at the frequency of applied waves, a second electron discharge device having electrodes coupled to said oscillator device to derive therefrom a voltage representative of the modulation of applied waves, means connected to the said oscillator input electrode adapted to cause the oscillator to function as a blocking oscillator whose blocking action is faster than the time of a half cycle of the highest wave frequency supplied to the receiver, and a modulation voltage utilization circuit coupled to the second device.

3. In a receiver of angular velocity-modulated carrier waves, a demodulator comprising a first electronic device having at least a cathode, a wave input electrode and an output electrode, means regeneratively coupling the output and input electrodes to provide an oscillator, means operatively associated with the oscillator nor-

mally to cause high peaks of output electrode current of short duration at a frequency close to the lowest wave frequency supplied to the receiver, a second electron discharge device having electrodes coupled to said oscillator device to derive therefrom a voltage representative of the modulation of applied waves, said second device having an input electrode coupled to the oscillator device input electrode, and a modulation voltage utilization circuit coupled to the second device.

4. In a receiver of angular velocity-modulated carrier waves, a demodulator comprising a first electronic device having at least a cathode, a wave input electrode and an output electrode, means regeneratively coupling the output and input electrodes to provide an oscillator operating at the frequency of applied waves, a second electron discharge device having electrodes coupled to said oscillator device to derive therefrom a voltage representative of the modulation of applied waves, means connected to the said oscillator input electrode adapted to cause the oscillator to function as a blocking oscillator whose blocking action is faster than the time of a half cycle of the highest wave frequency supplied to the receiver, said second device having an input electrode coupled to the oscillator device input electrode, and a modulation voltage utilization circuit coupled to the second device.

5. In a receiver of angular velocity-modulated carrier waves, a demodulator comprising a first electronic device having at least a cathode, a wave input electrode and an output electrode, means regeneratively coupling the output and input electrodes to provide an oscillator, means operatively associated with the oscillator normally to cause high peaks of output electrode current of short duration at a frequency close to the lowest wave frequency supplied to the receiver, a second electron discharge device having electrodes coupled to said oscillator device to derive therefrom a voltage representative of the modulation of applied waves, means connected to the said oscillator input electrode adapted to cause the oscillator to function as a blocking oscillator, said second device having an input electrode coupled to the oscillator device input electrode, and a modulation voltage utilization circuit coupled to the second device, said devices being separate electron discharge tubes, said second tube having an output electrode, and a charging condenser connected in circuit with the latter output electrode.

6. In a receiver of angular velocity-modulated carrier waves, a demodulator comprising a first electronic device having at least a cathode, a wave input electrode and an output electrode, means regeneratively coupling the output and input electrodes to provide an oscillator, means operatively associated with the oscillator normally to cause high peaks of output electrode current of short duration at a frequency close to the lowest wave frequency supplied to the receiver, a second electron discharge device having electrodes coupled to said oscillator device to derive therefrom a voltage representative of the modulation of applied waves, and a modulation voltage utilization circuit coupled to the second device, said second device being a diode rectifier, and the electrodes thereof being coupled to the output electrode and cathode of the oscillator device.
